UNITED STATES PATENT OFFICE.

CHARLES E. HEYER, OF CHICAGO, ILLINOIS.

DESIGN FOR A FONT OF PRINTING-TYPES.

SPECIFICATION forming part of Design No. 11,768, dated May 11, 1880.

Application filed March 20, 1880. Term of patent 7 years.

To all whom it may concern:

Be it known that I, CHARLES E. HEYER, of Chicago, in the county of Cook and State of Illinois, have originated and invented a new and useful Design for a Font of Printing-Types; and I do hereby declare that the following is a full, clear, and exact description thereof, reference being had to the accompanying printed impressions, forming a part of this specification.

My design is, in its nature, of an ornamental open-faced Greek character condensed and shaded, as clearly shown in the accompanying impression.

15 It consists of capital letters, figures, points, and two ornaments.

The letters and figures are formed with a hair-line on the left side, top, and bottom, and a black line on the right of the up-and-down strokes, with a fine shade-line at the right side of each. The letters terminate above and below in a triangular enlargement.

An additional characteristic of my design is that the letters A F J L V W X T have an upward scroll, and the letters K P Y Z a down-

ward scroll, these scrolls each ending in a dot, and being attached to the fine shade-line on the right side of the letters, except the J, to which it is attached at the left.

One ornament forms an outlined fan or shell projecting from the center of a perpendicular ornamental stroke. The other is an ornamental center-piece or cross elongated, consisting of three small circles centrally and transversely arranged, and elongated diamond-shaped upper and lower portions extending by tapering ends to or toward the center circle.

What I claim, and desire to secure by Letters Patent, is—

40 The design for a font of open-faced printing-types, as shown and described.

In testimony that I claim the foregoing as my own I affix my signature in presence of two witnesses.

CHARLES E. HEYER.
